UNITED STATES PATENT OFFICE.

ALEXANDER T. BROWN, OF SYRACUSE, NEW YORK.

BREECH-LOADING GUN.

SPECIFICATION forming part of Letters Patent No. 274,435, dated March 20, 1883.

Application filed February 9, 1883. (No model.)

To all whom it may concern:

Be it known that I, ALEXANDER T. BROWN, of Syracuse, in the county of Onondaga and State of New York, have invented certain new and useful Improvements in Breech-Loading Fire-Arms, of which the following is a specification, reference being had to the accompanying drawings, in which—

Figure 1 is a view of the breech of the gun with the stock removed and the barrels locked; Fig. 2, a longitudinal section of the breech-block and action with the stock and barrels removed; Fig. 3, a side view of the locking device removed from the breech-block, with the extension-rib in position for locking; Fig. 4, a rear perspective of the rotary lock and firing-pins separated from the breech-block; Fig. 5, a longitudinal section of Fig. 1; Fig. 6, a top plan view of the breech-block; Fig. 7, details of the extracting and joint-check mechanism.

My invention relates to that class of breech-loading fire-arms in which the mechanism for locking the barrels when the gun is closed is operated by a "top lever."

The objects of it are, first, to create a locking mechanism in which all horizontally-sliding bolts and all notches in the lug beneath the barrels to receive the locking-bolt are dispensed with; second, to throw back the firing-pins by the locking mechanism when the gun is unlocked; third, to eject the extractor by an eccentric in the lug beneath the barrels, and also to catch the barrels when broken down, and relieve the hinge-bolt from the dropping strain; fourth, to keep the rotary or oscillating lock open when the gun is unlocked and broken down ready to receive the extension-rib, until the rib in its downward movement in closing the gun reaches or nearly reaches the bottom of the rib-slot in the breech-block and in the rotary lock; fifth, to lock the gun by a rotary or oscillating lock engaging with an extension-rib; sixth, to lock the gun by a rotary lock engaging with an extension-rib and actuated by a lever; seventh, to create a cylindrical rotary lock slotted to receive an extension-rib; eighth, to actuate and control the action by a spring located in a slot within the breech-block closed by the trigger-plate.

It is constructed as follows:

A is the breech-block.

B is the barrel or barrels of the gun.

C is the extension-rib, constructed rectangular in section, and with the recess *a* in the back end, and the mortise *b* through the rib horizontally. This rib fits closely into a rectangular slot or mortise, *d*, in the breech-block.

D is the rotary or oscillating lock, constructed in the form of a cylinder, closed at one end and fitting loosely in a hole drilled from the back of the breech-block, under the tang, forward horizontally until it is deep enough to receive the rotary lock. Through the wall of this lock two slots, *e x*, connected at right angles to each other are cut, together making a T-shaped aperture, as shown in the drawings. That slot *e* corresponding to the top of the T is longitudinal of the rotary lock, and of the same width as the rib-slot in the breech-block. The slot *x* is circumferential, and of such width as to receive freely the bar *y* between the mortise *b* and recess *a* in the rib *C* and the tenon in the mortise *b*. The shell of the cylinder of the lock is of almost the same thickness as the height of the recess *a* or mortise *b*.

E is the lever by which the lock is operated, mounted upon the tang *F* of the breech-block and connected to the upright rod *f*, standing a little back of the breech-block, stepped at its lower end into the trigger-plate *h*, its upper end passing up through the tang.

H is a yoke with an arm attached, which yoke fits upon the rod *f*, and is fastened to it by a pivotal rivet or screw, as shown in the drawings. The outer end of this yoke-arm fits freely in a hole in the base of the rotary lock *D*, as shown in Figs. 1, 2, and 4.

I is an upright pin, having a shoulder on one side, fitted into a hole in the breech-block in the bottom of the rib-slot *d*, and having a spring behind it, as shown in Fig. 2. A recess is cut in the edge of the cylinder of the rotary lock large enough to receive the shoulder of the pin *I*. Upon the lower end of the rod *f* is a collar, *i*, having a shoulder or lug on one side; and *k* is a spring fitting into a recess in the bottom of the breech-block, just above the trigger-plate *h*, which closes the bottom of the recess.

K K are the firing-pins, having rods or pins *l* fitted into the sides of their heads. The points of these rods *l* fit into cam-recesses *m*

one on each side of the lock D in its periphery adjacent to the base. These recesses *m* are straight on that side longitudinal of the lock-cylinder D and curved on the other, as shown 5 in Figs. 2, 3, and 4.

M is an eccentric having a hole drilled in its periphery to receive the plug *n* and the spring behind it, as shown in Fig. 5. This plug *n* is hollow in its inner end to receive one end of 10 the spring shown, and has the shoulder *o* on its outer end. This shoulder is square on its front and two adjacent sides, while its top is rounded off from the front backward. In the 15 edges of the eccentric are the bearing-pins *pp*. This eccentric lies in a hole drilled crosswise 15 through the lug S beneath the barrels, and is of the same width as the lug. An opening is 20 cut from this hole through into the recess in which the extractor-pin lies, and large enough 25 to permit the shoulder *o* to pass through it into the extractor-recess and work freely.

N is the extractor, fitted into a recess between and beneath the barrels in the usual manner.

25 R is the hinge-bolt.

W is an L-shaped slot cut in the walls of and opening at *z* in the slot in the frame part of the breech-block, which receives the lug S. This slot is cut in both walls, first downward, 30 and then forward at right angles toward the front end of the frame. This slot is large or wide enough to freely receive the bearing-pins *p* on the eccentric M.

It is operated as follows: When the parts 35 are put together and the gun is closed and locked, the operation of unlocking the gun is as follows: The end of the lever E is pressed to the right. This revolves the rod *f*, carrying with it the yoke H and its arm. As it revolves 40 the yoke-arm bears against the side of the hole in the base of the rotary lock D and causes it to rotate until the rib C comes against the unbroken side of the upper part of the T-slot—that is to say, into the slot *e*—releasing 45 the mortise *b* and recess *a* from the tenons and slot *x*. Then the barrels are ready to be broken down, as shown in Fig. 5. At the same time that the rib C reaches the releasing-point 50 the shoulder on the pin I is thrown by the spring behind the pin into and engages with the recess in the edge of the rotary lock, as shown in Fig. 3; and by such engagement the rotary lock D is held in the unlocked position, the tension on the spring *k*, created by the revolution 55 of the rod *f* throwing the shoulder upon the collar *i* against the extremity of the spring, is retained, and the lever-arm is held over to the right. In this position the upper end of the rod I above the shoulder projects 60 upward into the open end of the rotary lock D, as seen in Fig. 3. When the gun is closed and locked the pins *p* on the eccentric M lie in the slot W toward its center; the extractor N is back in its recess, with the front side of the 65 shoulder *o* of the plug *n* behind it and bearing

against it. This eccentric M and extractor N remain stationary until the barrels are unlocked. Then, as the gun is opened and the lug S raised, the pins *p*, bearing against the upper side of the slot W forward of the open 70 part *z*, tend to retard the movement of the barrels, and would wholly retard them were it not that this retention imparts a rotary motion to the eccentric M, which permits the upward movement of that portion of the barrels behind the hinge and adjacent to the eccentric. At the same time this motion of the eccentric 75 throws the shoulder *o* forward against and ejects the extractor N. This motion continues, and the barrels continue to rise at that 80 point until the edge of the plug *n* in front of the shoulder *o* comes against the wall of the recess within which the eccentric M lies until the point of the shoulder *o* disengages from the extractor N, when the shoulder *o* comes 85 against the lug S, as shown in Fig. 5, and catches the barrels or stops their movement entirely, all sudden strain being thus taken off from the hinge-bolt R. At the same time, while the movement of the lever E sidewise 90 causes the rotation of the rotary lock D, this rotation brings the curved side of the recess *m* to bear against each of the rods *l* attached to the firing-pins K, and as the rotation continues forces the pins along the curved face 95 backward toward the base of the rotary lock D. In their backward movement the rods *l* carry with them the firing-pins K, withdrawing them far enough so that they are out of the way of the barrels and extractor when the 100 gun is opened.

The operation of closing or locking of the gun is as follows: The rib C is forced down into the slot *d* in the breech and the slot *e* in the rotary lock D until it strikes the upper 105 end of the pin I. As the rib is further forced down it depresses or pushes the pin I downward until just about the time when the rib reaches the bottom of the slot *d* on the lower side of the inside of the rotary lock D, the 110 shoulder on the pin I escapes from its recess, and the released rotary lock D, through the tension upon the spring *k*, is rotated, so that the slot *x* receives the bar *y* between the recess *a* and the mortise *b*, and the tenons on 115 each side of the slot *x* fill the recess *a* and mortise *b*, and the lever E flies back to its normal position. All of the parts take practically the 120 positions shown in Fig. 2. At the same time the extractor is forced back, and as the lug S 125 descends the point of the shoulder *o* in the plug *n* of the eccentric M is released from the lug, slips behind the end of the extractor, and by the motion of the eccentric the plug *n* finally assumes nearly an upright position 125 when the gun is closed, the spring behind the plug forcing the point of the shoulder *o* upward into the extractor-recess behind the extractor. It will be readily seen that when the gun is open the extractor can be pushed back 130

by hand without any trouble or danger. A set-screw is usually provided to prevent the loss of the extractor.

What I claim as my invention, and desire to 5 secure by Letters Patent, is—

1. In combination with an extension on the barrels of a breech-loading gun, an oscillating locking-bolt arranged with its axis in the direction of the axis of the barrels and to engage with the extension on the barrels by a 10 partial rotation, substantially as described.

2. The oscillating locking-bolt, having its axis in the direction of the axis of the gun, and having the T-shaped slot combined with 15 the extension on the barrels, substantially as stated.

3. A locking device for a breech-loading fire-arm, consisting of a rotary lock actuated by the operation of a top lever connected to an 20 upright revolving post behind the breech-block, and controlled by a spring, in combination with an extension-rib, substantially as described.

4. The oscillating locking device having 25 cam-surfaces, as described, combined with firing-pins having a bearing on said cam-surfaces, substantially as described.

5. In combination with the oscillating lock-

ing-bolt and rib, the spring-catch adapted to engage positively with the locking device until released by the rib, as set forth. 30

6. The oscillating locking-bolt having notch, the spring-pin engaging said bolt positively by entering the notch, and the rib on the barrels operating to disengage said pin, substantially as described. 35

7. The oscillating bolt slotted and notched, as described, the spring-pin, the operating-lever, and the extension on the barrels, all in combination, substantially as stated. 40

8. The lug on the barrels containing oscillating pin, as M, which is provided with eccentric extensions engaging in slots in the stock or frame to operate as a stop, as stated. 45

9. The lug on the barrels containing the oscillating pin having eccentric extensions engaging slots in the stock or frame, combined with the cartridge-ejector by suitable connecting mechanism, substantially as shown and set forth. 50

In witness whereof I have hereunto set my hand this 2d day of February, 1883.

ALEXANDER T. BROWN.
